UNITED STATES PATENT OFFICE.

ARTHUR L. MULL, OF RICHMOND, VIRGINIA, ASSIGNOR TO H. W. ROUNTREE & BROTHER
TRUNK AND BAG CO. INCORPORATED, OF RICHMOND, VIRGINIA.

CLOTHES FOLLOWER OR PRESSER.

1,302,069.

Specification of Letters Patent. Patented Apr. 29, 1919.

Application filed July 15, 1918. Serial No. 245,030.

To all whom it may concern:

Be it known that I, ARTHUR L. MULL, a citizen of the United States, residing at Richmond, in the county of Henrico and State of Virginia, have invented a new and Improved Clothes Follower or Presser, of which the following is a specification.

My invention, which generically has reference to wardrobe trunks, is more particularly directed to certain new and useful improvements in (what is termed in the art) followers or pressers that operate within that compartment of the trunk having garment supporting or hanger members, which improvements are especially designed to hold the garments in such manner to prevent them from being crumpled or mussed up while the trunk is in transportation or is set up to serve as a wardrobe.

20 Follower devices for wardrobe trunks, as heretofore constructed, have been of more or less complicated nature, especially when applied to the cheaper grades of wardrobe trunks, and more or less difficulty has been experienced in adjusting them to the desired clothes pressing or holding position.

In some types of follower or presser devices used in the garment compartment of wardrobe trunks, with which I am familiar, 30 such devices, to hold the top and bottom portion of the hanging garment, have been formed either of a frame arranged for being held against the garment by separate pressure applying and holding devices at the top and bottom portion and, in some instances, where free access to the garment compartment to remove or replace the garments, is desired, the follower devices proper need be wholly or partly bodily removed.

40 Again, in some of the appliances of the character stated and heretofore provided, the manipulation of the follower or presser devices has been so complicated that the handling thereof, especially when hanging ladies' dresses, is such, that great care must be taken so that the costly garments are not torn or otherwise damaged.

Primarily, my invention has for its object to provide a garment holding or pressing device for wardrobe trunks of a very simple and inexpensive construction in which the adjustment thereof, to its applied or released positions, is so simple, that any one can manipulate the same and the formation of the parts is such that danger of injury to

the hanging garments, of any character, is positively overcome.

In its more complete nature, my invention embodies a novel construction of garment presser and holding device, which, when its use is not necessary, can be quickly shifted to hang out of the way of access to the garment holding compartment.

Another and essential feature of my invention is the provision of a presser or follower device in which the follower element during the shifting operation of the device, first engages, presses and holds the lower part of the garment and, when shoved up to the limit of its pressure thrust, it remains locked for holding the lower part of the garment in place while the upper or other clamping portion of the device is swung up against the upper part of the garment, and locked in such position.

With other objects in view, all of which will be hereinafter brought out, my improved follower or presser device embodies certain details of construction and combination of parts, all of which will be first described in detail, specifically pointed out in the appended claims and illustrated in the accompanying drawings, in which:

Figure 1 is a perspective view of a wardrobe trunk to which my invention is applied, 85 the follower device being at the clothes pressing position.

Fig. 2 is a perspective view of the swingable presser or follower device hereinafter referred to.

Fig. 3 is a vertical section of a portion of the clothes compartment of the trunk, the presser or follower device being shown in full lines at the clothes pressing position, a dotted position indicating the manner in which the lower end of the device is forced inwardly against the lower portion of the garment and another dotted position indicating the position of the follower when dropped down and not in use.

Figs. 4 and 4^a are detail views of different forms of the upper locking guides herein-after referred to.

Fig. 5 is a detail view of one of the lower guides.

Fig. 6 is a detail view that illustrates the manner in which the locking elements on the fulcrum end of the follower device and the rack bar are coöperatively arranged.

grip ends of the latch bolts for the upper presser bar.

Fig. 8 is a detail perspective view of the free end of one of the side members and 5 means for interlocking the lower bar end therewith.

In the drawings, which illustrate a preferred form of my invention, 1 designates the garment compartment of a wardrobe 10 trunk of the conventional shape and in which my construction of presser or follower device is operatively assembled.

My construction of presser and follower device includes an upper presser member 15 that consists of a wooden bar 2 which extends crosswise and substantially the full width of the compartment 1, and an outer metallic casing 20 that includes longitudinally extended sockets 21—21 separated at 20 the center of the presser bar 2 and whose ends extend to the opposite ends of the said bar, as is shown in Fig. 1, by reference to which it will be also observed that a guide bracket 3, that forms a continuation of the 25 sockets 21—21 is attached to the presser bar and closes the gap between the inner ends of the said sockets 21—21.

A spring ejected lock bolt or rod is slidably mounted in each of the sockets 21—21, 30 they being held to the normal or locked position by the springs 5—5. The inner adjacent ends of the bolts 4—4 are bent to form finger grips 40—40 for being conveniently manipulated, when it is desired to withdraw the bolts 4—4 from their locked position to free the presser or follower member 2 for being swung up or down as may be desired.

For holding the pressure or follower bar 40 2 in its different clothes pressing adjustments, the opposite ends of the clothes compartment 1 are provided with locking plates 6—6, which may include a series of staggeredly arranged elongated slots 60—60, as 45 shown in Figs. 1, 3 and 4, or they may have ratchet elements 61, as shown in Fig. 4^a.

A combined guide and locking rack is located on each end of the clothes compartment 1, at a suitable distance below the upper locking plates 6—6.

Each of the combined guide and locking racks, one of which is shown in detail in Fig. 5, consists of a heavy sheet metal angled plate 7, the face portion 70 of which has a longitudinally elongated guide slot 71, the purpose of which will presently appear.

The said combined guide and locking member also includes a rack bar 72 that is 60 riveted or otherwise secured along the inner side of the lower edge of the plate 7, with the upper edge of the teeth 73 thereof disposed in a plane below the lower edge of the guide slots 71, as is clearly shown in Fig. 5. 65 8 designates, what is hereinafter termed,

the lower follower or presser bar, which bar, is preferably of wood and has its ends reinforced by metal guide loops 9—9 which slidably engage opposite end rods 10—10 whose outer ends are fixed on the outer ends of the 70 upper presser bar 2.

The lower end of each of the rods 10 includes a flattened portion 11 and terminates in an outwardly extended angled member 12 adapted for loosely projecting through 75 and riding along the slot 71, the flattened portion 11 extending along the rod 10 a distance from the angled member 12 slightly greater than the width of the presser bar 8, the upper end of the said portion 11 terminating in an abrupt shoulder 13, as shown.

A locking pawl or dog 14 is secured upon the outer end of each rod member 12 for engaging with the rack bar 72, when the top presser bar is swung up and is held pressed 85 against the clothing, as will be presently more fully explained.

Forming the ends of the side rods 10—10 with flattened portions 11 and shoulders 13, causes the metal end loops 9—9, on the lower 90 pressure bar 8, to seat upon the flattened portions 11 of the said rods 10, when the follower device is swung to the horizontal position shown in dotted lines in Fig. 3 and, when the follower device is thus positioned, 95 the shoulders 13—13 hold the said bar 8 from sliding outwardly on the rods 10, when pressure is applied in the direction of the arrow 15 for forcing the bar 8 against the lower portion of the clothing. 100

Furthermore, since the loops 9—9 freely engage the said bars 10, when the follower device is swung to the hanging or inoperative position, as shown in dotted lines on Fig. 3, the bar 8 drops onto the (now bottom) bar 2, it being understood that, when the two bars 8 and 2 are in the last stated position, a free clearance of the clothes holding compartment is provided for readily hanging or removing the clothing without 110 danger of the same coming in contact or entangled with the presser devices.

By reason of the peculiar construction of my follower or presser device, assuming it to be now at the hanging or inoperative position, when it is desired to apply the same for holding a few or a number of dresses or other garments supported from the overhead hangers 16—16 in the usual way, by gripping the bar 2 with one hand, withdrawing the spring latch rods and swinging the device to the horizontal position shown in Fig. 2, the lower bar 8 can then be readily slid along the side rods 10—10 to interlock with the ends of the said rods and their 120 shoulders 13.

When thus positioned, the ends 12—12 of the side rods 10—10 ride freely in the guide slots 71 of the end members 7, thereby providing for pressing the lower bar against 130

the lower portion of the garment and, when the desired pressure is obtained, the device is swung up (the members 12-12 now constituting fulcrums) to bring the upper bar 5 into contact with the garments and, as the fulcrum members 12-12 now rock on the lower edges of the slots 71, the pawls or dogs 14, by reason of their peculiar shape, as shown, interlock with the rack bar 72 10 and thereby hold the lower bar from being forced back along the end guides 7-7.

After pressing the top bar against the clothing as desired, by releasing the finger members of the locking rod, the latter slide 15 out and interengage with the lock plates 6-6 on the opposite ends of the garment chamber.

To remove the presser or follower device, to allow free access to the clothing compartment, the spring latch rods are withdrawn and the upper bar is swung down to the horizontal position for releasing the dogs on the ends of the members 12-12 25 from the ratchet bars, after which the said device is pulled back until the angled portions 12-12 of the rods 10 contact with the front end of the slots 71-71, each of which slots has a seat or depression 75 at the outer end and, when the said ends 12-12 engage 30 with the said seats, by then releasing the device, the side arms 10-10 swing down by gravity with both the upper and the lower presser members located at the bottom end 35 of the clothes compartment, it being understood that the presser bar 8 drops to the position shown in Fig. 1 and out of the way.

Since the construction of the trunk body and the clothes hanging elements are of a well known form, a detail description of the 40 parts thereof has not been given.

What I claim is:

1. A follower device for garment compartments of wardrobe trunks comprising in combination with upper and lower pairs of 45 guides on the opposite walls of the garment compartment; an upper presser bar, side arms attached thereto having their free ends horizontally slidably engaging the lower set of guides and forming fulcrums, means for locking the said free ends of the side arms 50 at their slidably adjustable positions on the said set of lower guides and finger released latches on the upper bar that normally interlock with the upper pair of guides, when 55 the device is swung up to the closed position.

2. A follower device for garment compartments of wardrobe trunks, comprising in combination with upper and lower pairs 60 of guides on the opposite walls of the garment compartment; an upper and a lower presser bar, side arms attached thereto having their free ends shaped for sliding horizontally on the lower set of guides and to 65 form fulcrums, and finger released latches

on the upper bar that normally interlock with the upper guide bars, when the device is swung up to its closed position, the said lower presser bar being slidably mounted on the said side arms, and means on the arms 70 and the lower presser bar for holding the said bar at the outermost ends of the said arms and coöperating means on the lower ends of the side arms and the lower set of guides for holding the device in pressing 75 position.

3. A follower device for garment compartments of wardrobe trunks, comprising in combination with upper and lower pairs of guides on the opposite walls of the garment compartment; an upper and a lower presser bar, side arms attached thereto having their free ends shaped for sliding horizontally on the lower set of guides and to 80 form fulcrums, and finger released latches on the upper bar that normally interlock with the upper guide bars, when the device is swung up to its closed position, the said lower presser bar being slidably mounted on the said side arms, and means on the arms 85 and the lower presser bar for holding the said bar at the outermost ends of the said arms, the said lower guides having seat portions at the outer ends for receiving the fulcrum ends of the bars, whereby to adapt the 90 follower device to hang down out of the way, when not in use and coöperating means on the lower ends of the side arms and the lower set of guides for holding the device 95 in pressing position. 100

4. A follower device for garment compartments of wardrobe trunks, comprising in combination with upper and lower pairs of guides on the opposite walls of the garment compartment; an upper and a lower presser bar, side arms attached thereto having their free ends shaped for sliding horizontally on the lower set of guides and to 105 form fulcrums, and finger released latches on the upper bar that normally interlock with the upper guide bars, when the device is swung up to its closed position, the said lower presser bar being slidably mounted on the said side arms, and means on the arms 110 and the lower presser bar for holding the said bar at the outermost ends of the said arms, the said lower guides each including a horizontal guide slot and a rack bar, and members on the fulcrum ends of the side arms of the follower device adapted for 115 interlockably engaging the rack bar, when the follower device is swung up to its clothes 120 pressing position.

5. A follower device for garment compartments of wardrobe trunks, comprising in combination with upper and lower pairs of guides on the opposite walls of the garment compartment; an upper and a lower presser bar, side arms attached thereto having their free ends shaped for sliding hori- 125 130

zontally on the lower set of guides and to form fulcrums; and finger released latches on the upper bar that normally interlock with the upper guide bars; when the device 5 is swung up to its closed position; the said lower presser bar being slidably mounted on the said side arms, and means on the arms and the lower presser bar for holding the said bar at the outermost ends of the said 10 arms, the said lower guides each including a horizontal guide slot and a rack bar, and members on the fulcrum ends of the side arms of the follower device adapted for in-

terlockably engaging the rack bar, when the follower device is swung up to its clothes pressing position, the said rack bars being in a plane below the said slots; the said rack bar interlocking members including tooth portions that ride over the said rack bars; when the follower device is lowered 15 for sliding the lower presser bar inwardly and which project down into the said rack bar, when the presser device is swung up to apply the top presser bar.

ARTHUR L. MULL.
